UNITED STATES PATENT OFFICE.

OLIVER NOLAN, OF ST. PAUL, MINNESOTA.

MACHINE FOR MOLDING CONCRETE BUILDING-BLOCKS.

1,151,531.

Specification of Letters Patent. Patented Aug. 24, 1915.

Application filed June 27, 1913. Serial No. 776,026.

To all whom it may concern:

Be it known that I, OLIVER NOLAN, a citizen of the United States, residing at St. Paul, in the county of Ramsey and State of Minnesota, have invented new and useful Improvements in Machines for Molding Concrete Building-Blocks, of which the following is a specification.

My invention relates to improvements in machines for molding concrete blocks of the class described in my application for patent filed in the Patent Office on July 1st, 1912, bearing Serial No. 706,917.

The object of my present invention is to provide an improved machine of that kind capable of rapid, easy and continuously efficient operation.

In the drawings, Figure 1 is a perspective view of my complete machine; Fig. 2 is a vertical central section in detail of the same; Fig. 3 is a plan view of the assembled machine partly broken away to show certain parts thereof, and Figs. 4 and 5 are detail perspective views illustrating the mold sections.

Referring to the drawings, I have used the reference numeral 10 to indicate the frame. This frame consists of angular uprights or guides 11, braces 12 for said uprights and a pair of parallel sills 13 adapted to support a pallet 14 on which a concrete block may be formed.

The mold 15 consists of mold sections 16 and 17 and is adapted to telescope upon the frame 10. The mold section 16, which for convenience will be called the primary mold section, is formed of plates 18 and 19, base bars 20 and 21 and angular bearing supports 22 extending downward from the lower corners of said section, all of said parts being integral, as shown in Fig. 4. The bearing supports 22 are each supplied with a plurality of set bolts 23 adapted to serve as adjustable bearings and move upon the guides 11, thus directing the vertical movement of the mold section 16 on the frame 10. The mold section 17, which may be termed the secondary mold section, consists of plates 24 and 25, each being formed with an irregular inner face and provided with a detachable lining 26, which when attached to said plates, form smooth faces therefor. Lugs 27 on the ends of the plates 24 and 25 rest in the slideways 28 at the ends of the plates 18 and 19 of the primary mold section. The bracket 29, located at the junc-

tion of the base bars 20 and 21, is supplied with horizontal pins 30 slideable in the secondary mold section 17. These pins form guides for said mold section 17 and together with the lugs 27 in the slideways 28 provide a horizontal mounting on which said section 17 moves. A plurality of cores 31 are each adjustably secured by a clamp 32 to the core beam 33 on the primary mold section 16.

To reciprocate the mold and cores upon the frame 10 and to hold the same in their elevated and lowered positions, I have provided the following mechanism: Two horizontal shafts 34, revoluble in the frame 10, are arranged in parallel relation to each other at equal distances from the vertical central plane of the mold 15. Similarly arranged arms 35 are attached and extend at right angles to each shaft. Upwardly extending hangers 36, secured to the ends of the primary mold section 16, are pivotally connected by links 37 with the adjacent arms 35 on the shafts 34, all the points of connection between said links and hangers being arranged in a horizontal plane and equidistant from the vertical central plane of the mold 15. Two gear sectors 38, one on each shaft 34, mesh to transmit power from one shaft and turn the other shaft in the reverse direction. A hand lever 39, applied to one of the arms 35, is provided for turning the shaft to which said arm is attached. By moving the hand lever 39 in one direction power is applied through the arms 35 and links 37 upon each hanger 36, equally and in opposite directions, thus resulting in a vertical lift at each end of the mold. It will be noted that the points of connection between the links 37 and hangers 36 are a substantial distance above the bearings 23 in the mold section 16 and that for this reason slightly inaccurate movements of the links 37, due to lack of exact uniformity in the parts of the lifting mechanism, are unimportant because they do not result in binding between the bearings 23 and the guides 11 of the frame. Attention is also directed to the fact that the bearings 23 in the mold section 16 space the bearing supports 22 a sufficient distance from the frame 10 to prevent the clogging of concrete between the mold and frame. The mold 15 is held at the end of its upper stroke by moving the hand lever 39 to a position locating the links 37 against the stops 40 on the mold section 16, wherein the centers of each arm 35 and its

link 37 are substantially in alinement. The spring catch 41 on one of said stops, engages one of the links 37 and serves to lock the lifting mechanism, thus securing the mold 15 in elevated position. The hand lever 39 is moved to lower the mold and cores and permit the removal of a molded block and its supporting pallet from the frame 10. Stop bars 42 on the frame 10 are placed in the paths of the bearing supports 22 to limit the downward movement of the mold 15. It is evident that if no counterpoise were employed considerable power would have to be applied to the hand lever 39 to raise the mold 15 and cores 31 upon the frame and that care would be necessary in lowering the mold to prevent jarring of the machine and consequent injury to a molded block as the mold strikes its stop bars. To render this operation easy and more efficient, I have provided a pair of coiled springs 43, each spring being attached at one end to the frame with its free end in sliding engagement with the core bar 33 of the mold. These springs are of sufficient strength to practically counterbalance the mold 15, with the result that only a slight amount of power is required to move the mold and close attention in lowering the same is unnecessary.

30 My machine is adapted to form ordinary smooth concrete blocks or blocks having one or more ornamental or imitation cut stone faces. In forming a smooth block, the pallet 14 is placed on the sills 13, and the mold elevated as illustrated in Fig. 1 of the drawings. The linings 26 are attached to the plates 24 and 25 of the mold section 17 and concrete is supplied to the mold 15 and tamped in the usual manner. The hand lever 39 is then manipulated to lower the mold and cores and thus permit access to the newly formed block which may be removed upon its pallet. Downward vertical movement of the mold causes the plates 18, 19, 24 and 25 to trowel and thereby finish the surface of the block.

50 In constructing blocks with irregular faces, the linings 26 are removed from the plates 24 and 25 and the mold is filled as above described. It is evident, however, that immediate downward movement of said mold would cause the irregular projections to be sheared from the face of the block. I avoid such damage by moving the secondary mold section 17 horizontally from the sides of the block before the mold is lowered. This horizontal movement of said secondary mold section 17 is accomplished by the following described mechanism which also locks the mold sections 16 and 17 together: 55 A latch 44, having a catch 45 and a projection 46, is provided for each lug 27 of the mold section 17, said latches being pivotally mounted on the mold section 16 in position adjacent to their respective lugs. A lever

47, provided with a handle 48 at one end, is pivotally supported on the mold section 16 and is slidably and pivotally connected at its other end with one of said latches. An arm 49, slidably and pivotally connected at one end with the other latch, is pivoted on the mold section 16 and is furnished at its other end with a pintle 50 which protrudes through the perforation 51 in the lever 47 to form a connection with said lever. Manipulation of the lever 47 upwardly moves the latches 44 in a direction causing the projections 46 to bear against the lugs 27 on the plates 24 and 25. This pressure against said plates 24 and 25 brought to bear by the two latches 44, which are arranged at right angles to each other, results in the free movement of the secondary mold section upon the guides 30 and the slideways 28 of the primary mold section away from the sides 18 and 19 of said section. Downward movement of the lever 47 turns the latches 44 in a direction to cause the catches 45 to strike the lugs 27. The engagement of the catches with said beveled lugs brings about the return of the secondary section 17. Continued downward movement of said lever 47 registers the latches 45 with the notches 52 in the lugs 27 as illustrated in Fig. 1, thereby firmly securing the secondary mold section 17 against horizontal movement on the primary mold section. The separating and joining of the mold sections 16 and 17 is readily accomplished by manually operating the lever 47. It is desirable, however, to automatically join and lock the sections 16 and 17 when the mold is lowered on the frame. To accomplish this end, I suspend from each of the latches 44 a bar 53 adapted to impinge against a stop 54 on the frame. During the completion of the downward stroke of the mold, these bars strike said stops and turn said latches to engage the lugs 27, thus joining and locking the mold sections 16 and 17 together.

Having described my invention, what I claim as new and desire to protect by Letters Patent, is:

1. In a device of the class described, the combination of a frame, a pallet removably supported on said frame, a mold slidable vertically on the frame and having separable sides, means for manually separating said sides, means for raising and lowering the mold on the frame, yielding means in operative connection with said mold for counterbalancing the same and mechanism for automatically joining and locking the sides of said mold as it approaches the end of its downward stroke.

2. In a device of the class described, the combination of a frame, a pallet removably supported on said frame, a mold slidable vertically on said frame and having separable sides, means for manually separating

the sides and moving the same in paths diverging from the remaining sides of the mold, means for raising and lowering the mold on the frame and mechanism for automatically joining and locking the sides of said mold as it approaches the end of its downward stroke.

3. In a machine for molding concrete blocks, a frame, a mold on said frame having fixed and separable sides, means for moving said separable sides to open the mold, mechanism for raising and lowering all of said sides, and means for automatically joining and locking said sides to securely close the mold as the same is lowered.

4. In a device of the class described, the combination of a frame having vertical slides thereon, a pallet removably supported on said frame, a mold adapted to telescope over said frame, bearing supports extending downward from said mold, bearings on said supports adapted to move upon said slides and space said mold from said frame, upwardly extending hangers on the mold, and means attached to said hangers for raising and lowering the mold with respect to the frame.

5. In a device of the class described the combination of a frame, a mold having a 30 slide bearing on said frame and adapted to move vertically thereon and means for

raising and lowering said mold, said means being attached to the mold above said mold bearing.

6. In a device of the class described, the combination of a frame, a pallet removably supported on said frame, a mold slidable vertically on the frame and formed with a plurality of separable sides, horizontal guides on said mold for said separable sides, 40 adapted to direct the same in paths diverging from the remaining sides of said mold, means for moving said separable sides to open the mold and means for elevating and depressing said mold.

7. In a device of the class described, the combination of a frame, having bearing slides thereon, a mold adapted to move vertically with respect to said frame, a plurality of bearings on the mold, beneath the 50 body thereof, adapted to bear upon said body, adapted to bear upon said bearing slides and actuating devices attached to the mold at points above said mold bearings.

In testimony whereof, I have signed my 55 name to this specification in the presence of two subscribing witnesses.

OLIVER NOLAN.
